BOBBY PIN WITH EXPANDER

Layne O. Hodson, Layton, and Blaine W. Wilson,
Salt Lake City, Utah

Application January 22, 1948, Serial No. 3,684

3 Claims. (Cl. 132—50)

1

This invention relates to resilient hair pins commonly known as bobby pins and widely used by girls and women to retain both long and short hair in pleasing contours on their heads.

Bobby pins made by various manufacturers differ somewhat in size and shape, but all are resilient and are formed from a flat and narrow strip length of material bent upon itself to provide an open loop terminating in a pair of long clip members which serve to grip and hold in place a wide swath of hair.

In using these bobby pins, however, considerable difficulty has been encountered in opening the clip members for application to the hair, because the resilient nature of the pin makes for normal maintenance of tight closure of the clip members with respect to each other. It is customary for women to open the clip members with finger nails or teeth, and often finger nails are broken and teeth chipped by such practice.

Recently various devices have appeared on the market for facilitating opening of the clip members immediately prior to use. For example, a finger ring is available which may be worn by a beauty parlor operator during working hours, the ring embodying a formation against which the separable ends of bobby pins are brought to bear so as to force the tightly closed clip members thereof apart. Again, a wedge-formed shield is available for insertion over the front teeth of a bobby pin user to similarly facilitate opening of the clip members of the bobby pin and to safeguard the teeth against injury.

All such devices are clumsy to use and a nuisance, especially for the individual user who works only with her own hair and, perhaps, with the hair of her children. More likely than not, the device is misplaced at the very time it is needed, and its use is seldom justified for the few bobby pins applied personally.

The present invention provides a bobby pin and expander combination to be sold and used as an integrated unit, the expander being always attached to and forming an operative part of the bobby pin itself, and being limited in its travel to effectively accomplish its purpose during use.

Pursuant to the invention, there is secured within the loop portion of each bobby pin, at the bend thereof, a substantially rigid slide element, which may be grasped by the fingers of the user at the moment of application of the bobby pin to the hair and pushed forwardly a limited distance along and between the convergent leg members of the loop, as a wedge, thereby easily forcing the pair of clip members apart, without obstructing the open, hair-insertion end of the bobby pin.

2

As the pin is pushed over the strand of hair, the slide element is forced back to the bend of the loop portion, thereby allowing the clip members to snap together over the strand. Thus each bobby pin embodies as a part of its structure movable wedge means for readily and conveniently expanding the clip members thereof.

Accordingly, a principal object of the invention is to provide a bobby pin which embodies its own expander for limited action to uniformly achieve optimum results during use.

An object is to provide a bobby pin and expander combination that is simple and positive in operation.

15 An object is to provide such a combination capable of high speed, low cost mass production.

Further objects and features will become apparent from the following detailed description of the illustrated preferred forms of the invention.

20 In the drawing:

Fig. 1 represents a side elevation of one of the preferred forms;

Fig. 2, a bottom plan view;

Fig. 3, a vertical section taken on the line 3—3;

25 Fig. 1;

Fig. 4, a perspective view taken from the bend or loop end;

Fig. 5, a view showing the wedge element being pushed forwardly to expand or open the clip members;

30 Fig. 6, a perspective view showing the manner of application of the bobby pin combination to the hair;

Fig. 7, a view similar to that of Fig. 1, but illustrating a somewhat different embodiment of the invention;

Fig. 8, a fragmentary top plan view of the embodiment of Fig. 1;

Fig. 9, a fragmentary side elevation of another embodiment of the invention;

40 Fig. 10, a top plan view of the structure shown in Fig. 9;

Fig. 11, a view corresponding to that of Fig. 9, but illustrating the expander pushed forward to open the bobby pin; and

45 Fig. 12, a vertical section taken on the line 12—12, Fig. 9.

Referring now to the drawing: the embodiment of Fig. 1 includes a bobby pin 10, essentially of conventional formation, and a traveler or expander block 11 of wedge formation. The bobby pin 10 is resilient, and is formed in customary manner from a length of flat strip or wire. It possesses a loop member 12 which terminates in a pair of long clip members 13 and 14. The loop member 12 is elongate, having leg portions 12a

and 12b converging together from the loop bend. The leg portion 12b merges into the clip member 14 in aligned relationship therewith, the two forming a substantially rectilinear strip along the length of the pin. The leg portion 12a slopes toward the leg portion 12b, converging therewith, and merges into the clip member 13 angularly or arcuately. The clip member 13 lies parallel with the clip member 14, and is held tightly thereagainst by the inherent resiliency of the bobby pin structure as a whole. Its free tip 13a is curved somewhat to provide an open mouth 15, which facilitates insertion of a strand or tress of hair.

The expander 11 is in the form of a wedge-shaped block slide which acts as a wedge in forcing the two clip members of the bobby pin apart. It is normally positioned within the loop portion 12 of the bobby pin with maximum dimensions disposed at the loop bend, and is anchored for sliding movement longitudinally. The leg portion 12b of the pin passes through a longitudinal slideway defined by a band member 16, Fig. 3, and the base of the block. Thus, the expander 11 is both secured to and has its movement guided relative to the bobby pin 10.

The sloping wedge surface of the block is advantageously slightly arcuate, so that the leg portion 12a of the pin makes substantially a tangential contact therewith, as indicated at 17, Fig. 1, and the sides of the block are advantageously roughened in some suitable manner to provide effective gripping surfaces. A projection 18 is provided on the clip member 14 as a stop member for coaction with the band 16 in limiting sliding movement of the expander 11 and preventing travel thereof beyond the point of maximum expansion of the pair of clip members. The projection 18 is properly located for that purpose.

In preparing the bobby pin 10 for use the expander 11 is pushed forwardly, as in Fig. 5, thereby opening the clip members 13 and 14. The opened bobby pin is then applied to a tress of hair in customary manner, as in Fig. 6, the expander 11 being forced back to the loop bend of the loop portion 12 of the bobby pin by entry of the hair.

As illustrated in Figs. 7 and 8, the bobby pin may be of the type where one of the clip members is crimped throughout its length. Thus the crimps of clip member 20 do not impair the effective operation of the expander block. In this instance the expander block 21 is shown of somewhat different formation merely to illustrate a permissible variation. It is not wedge shaped, as is the block 11, and is anchored merely by pairs of ears 22 which may be provided at both slide faces thereof, as shown, or merely at one. One of the pair of ears, indicated 23, may be inturned, as shown, to overlie the leg portion 24 of the loop member and to utilize the first crimp 20a of the clip member 20 as a limit stop.

The embodiment of Figs. 9, 10, 11, and 12 employs an expander slide 25 of a formation essentially concentric with the bend of the loop member 26 of the bobby pin. The slide is externally channeled, as at 27, Fig. 12, to mate snugly with said bend of the loop member of the bobby pin and with the respective legs thereof for movement to separate the clip members 28 and 29. An inwardly directed crimp in the clip member 29 is provided in the illustrated instance as a limit stop, the same being accommodated by a corresponding crimp of the clip member 28 when the bobby pin is closed.

In operation, the two embodiments last described work similarly to that first described.

The expander slides of all embodiments may be molded to satisfactory shape from metal or from a substantially hard-setting plastic.

Whereas this invention is here illustrated and described with respect to certain preferred specific embodiments thereof, it should be understood that various changes may be made in said embodiments and various other embodiments that may be designed on the basis of the teachings hereof by those skilled in the art without departing from the generic scope of the invention as defined in the following claims.

15. What is claimed is:

1. In combination, a bobby pin having a loop member and a pair of elongate clip members extending therefrom and normally resiliently urged together in closed contacting relationship, the said loop member being gradually convergent from its loop bend to the said closed clip members; a clip-expanding traveler fitted into said open loop member, said traveler having a portion thereof of size accommodated by said loop bend portion of the loop member, but too large to be accommodated by the convergent portion of said loop member without separating the clip members of the bobby pin, the said portion of the traveler being normally disposed at and within said loop bend portion, but being movable along said convergent portion of the loop member for expanding said bobby pin to open position; and a pair of coacting limit stop members associated with the said traveler and with one of said clip members, respectively, that limit stop member which is associated with the said one clip member being disposed adjacent the termination of convergence of said loop members, so as to be positioned intermediate the length of said bobby pin to limit outward travel of said traveler to substantially the position of maximum separation of said clip members.

2. The combination recited in claim 1, wherein the traveler member is formed with a band providing a closed slideway which receives a corresponding clip member of the bobby pin, and wherein one of the pair of limit stop members is provided by said band and the other is associated with the said corresponding clip member.

3. The combination recited in claim 1, wherein one clip member of the bobby pin is outwardly crimped along its length, and the other clip member has an inward crimp adapted to nest with one of the outward crimps of the said one clip member when the said clip members are closed, the said inward crimp serving as a limit stop for the traveler member.
